UNITED STATES PATENT OFFICE

ARTHUR W. CONLEY, OF CLEVELAND HEIGHTS, OHIO

DESIGN FOR AN OZONIZER

Application filed March 18, 1930. Serial No. 34,953. Term of patent 14 years.

To all whom it may concern:

Be it known that I, ARTHUR W. CONLEY, a citizen of the United States, residing at Cleveland Heights, in the county of Cuyahoga and State of Ohio, have invented a new, original, and ornamental Design for an Ozonizer, of which the following is a specification, reference being had to the accompanying drawings, which form a part thereof, and in which—

Figure 1 is a side elevational view of an ozonizer showing my new design, while Figure 2 is a top plan view of the same.

I claim:

The ornamental design for an ozonizer substantially as shown.

ARTHUR W. CONLEY.
